(57) **CLAIM**

The ornamental design for a shipping container, as shown and described.

DESCRIPTION

FIG. 1 is a perspective view of a shipping container.
FIG. 2 is a top view of a shipping container as shown in FIG. 1.

FIG. 3 is a bottom view of a shipping container as shown in FIG. 1.

FIG. 4 is a side view of a shipping container as shown in FIG. 1.

FIG. 5 is an opposite side view of a shipping container as shown in FIG. 1.

FIG. 6 is a front view of a shipping container as shown in FIG. 1.

FIG. 7 is a back view of a shipping container as shown in FIG. 1; and,

FIG. 8 is a front cross-sectional view of a shipping container as shown in FIG. 1-taken along lines 8-8 of FIG. 4.

Throughout FIGS. 1-8, the broken lines denote environment and aspects of the container and formative components that form no part of the claimed design.

1 Claim, 8 Drawing Sheets
